(57) **CLAIM**

The ornamental design for a dental trainer rest, as shown and described.

DESCRIPTION

FIG. 1 is a front-top-right perspective view of a dental trainer rest;

FIG. 2 is a front-top-left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view thereof, showing the dental trainer rest as part of an exemplary dental training device.

The broken lines illustrate unclaimed and/or environmental features that form no part of the claimed design.
